(No Model.)

J. MARET.
MUSIC LEAF TURNER.

No. 443,626.

Patented Dec. 30, 1890.

FIG. 1.

UNITED STATES PATENT OFFICE.

JAMES MARET, OF MOUNT VERNON, KENTUCKY.

MUSIC-LEAF TURNER.

SPECIFICATION forming part of Letters Patent No. 443,626, dated December 30, 1890.

Application filed March 22, 1890. Serial No. 344,915. (No model.)

To all whom it may concern:

Be it known that I, JAMES MARET, of Mount Vernon, in the county of Rock Castle and State of Kentucky, have invented a new and 5 Improved Music-Leaf Turner, of which the following is a specification, reference being had to the annexed drawings, forming a part thereof, in which—

Figure 1 is a front elevation, partly in section and broken away, of my improved music-leaf turner. Fig. 2 is a vertical transverse section taken on line 2 2 in Fig. 1. Fig. 3 is a horizontal section taken on line 3 3 in Fig. 1, and Fig. 4 is a perspective view of the end 15 of one of the springs.

Similar letters and figures of reference indicate corresponding parts in all the views.

The object of my invention is to construct an instrument for turning the leaves of music 20 in which the leaves may be turned in succession by the liberation of spring-actuated arms; also, to provide a leaf-turner in which the arms may be used independently of each other.

25 My invention consists in the combination of a series of fixed ratchets and a series of sleeves carrying leaf-turning arms and provided with volute springs furnished at their outer ends with hooks adapted to engage the 30 fixed ratchets.

The invention also consists, further, in the combination, with the leaf-turning arms, of clasps for engaging the leaves of music, and of spring-catches for holding the arms, all as 35 will be hereinafter more fully described.

To the back-board A is attached the metallic plate B, to which are secured fixed ratchets C, having notches *a* in their outer edges, and provided with pairs of pins *b* in 40 their upper surface opposite the notches. Upon a rod extending upwardly from the lower ratchet through the other ratchets are placed sleeves E, which carry the arms 1 2 3 4, and to each sleeve is secured the inner end 45 of a volute spring F, upon the outer end of which is formed the hook *c* for engaging the ratchet C. It is also provided with a handle *d*, used in changing the tension of the spring. The lower arm 1 is bent downwardly at right 50 angles at its free end, and provided with a spring-operated clasp *e*, formed of the plates *ff'*, hinged together and furnished with a

rubber lining *g*. The arm 1 is also provided with an auxiliary arm *h*, which carries a clasp *e*, like that already described. The remaining arms 2 3 4 are bent at right angles at their free ends, and differ in length so that they reach one over the other, as shown in Fig. 1.

The arms 1 2 3 4 are provided with catches 6c *i*, which pass through apertures in the back-board A and are engaged by angled catch-levers 5 6 7 8, pivoted to the back of the board A at 9 10 11 12. The upper ends of the catch-levers 5 6 7 8 pass through loops *j*, secured to 65 the back of the board A, and are pressed upwardly by spiral springs *l*, arranged in the loops. The lower ends of the catch-levers are bent outwardly and extend through slots in the back-board A, and are provided with 70 knobs or keys *k*.

The back-board A is provided with a shelf G for receiving the music or music book. In a hole *m* in the shelf G is inserted a rod D, the upper end of which extends a short distance into a socket *n* on the under surface of the lower ratchet C. The rod D is held in the position of use by the spring *o*, attached to the under side of the shelf G.

The rod D is used for holding sheets of 80 music or music-books on the board A. The edges of the leaves of music are received in the clasps *e*, and the arms 1 2 3 4 are held by the catch-levers 5 6 7 8 until they are liberated by pressing the keys *k* from left to 85 right, when the arms are turned by the springs F. Spring-clips *a'* are provided for holding the edges of the first and last leaves of a piece of music against the board A.

It will be observed that either of the arms 90 may be used independently of the others, so that if any portion of the instrument should get out of order the remainder may be used without inconvenience.

When it is desired to increase the tension 95 of the spring F, the free end of the spring is carried around and brought into engagement with another notch in the ratchet C, at the same time being placed between the pins *b* opposite that notch.

Having thus described my invention, I claim as new and desire to secure by Letters Patent—

1. The combination, with the board having

a vertically-apertured ledge or shelf and a spring beneath said aperture, of a rod for holding sheet-music, having its lower end within said aperture and resting on said 5 spring, and a bearing for the upper end of the rod, whereby by pressing the rod downward and laterally it may be disengaged from said bearing.

2. In a music-leaf turner, the combination 10 of the fixed ratchets C, provided with the pins b, the springs F, the sleeves E, the arms 1 2 3 4, provided with clasps e and catches i, and the spring-pressed catch-levers 5 6 7 8, substantially as specified.

15 3. In a music-leaf turner, the combination, with the board having a ledge or shelf apertured at m and provided with a spring, and the leaf-turning mechanism mounted on the

board and having a lower fixed part provided with a socket n on its lower face, of a rod 20 resting at its lower end on said spring and at its upper end in the said socket, substantially as set forth.

4. In a music-leaf turner, the combination of the fixed ratchet C, provided with pins b, 25 the spring F, furnished with the hooked end e and the handle d, the sleeve E, and the leaf-turning arm, substantially as specified.

5. In a music-leaf turner, the combination, with a leaf-turning arm and means for holding and releasing said arm, of an adjustable 30 spring, substantially as specified.

JAMES MARET.
